UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Application filed Setember 8, 1930. Serial No. 480,395.

My invention relates to a slicing machine, for example a machine adaptable for slicing meat, bread, vegetables and the like, and has for one object the provision of a machine which shall be light and quick and easy to operate. Another object is the provision of a machine in which the work being sliced tends to recede from the cutting plane of the knife, when released. Another object specifically, is the provision of such a machine with means for holding the work in such fashion and at such an angle that it will tend by gravity to recede from the knife, unless positively thrust thereagainst. Another object is the provision of means for positively thrusting the work, against gravity, toward the cutting plane. Other objects will appear from time to time in the course of the specification and claims.

I illustrate my invention more or less diagrammatically in the accompanying drawings, wherein:

Figure 1 is a plan view looking in the direction of the arrow 1 on Fig. 2 with parts in section;

Figure 2 is an end view with parts broken away;

Figure 3 is a side elevation looking in the direction of the arrow 3 on Fig. 2; and

Figure 4 is a section on the line 4—4 of Figure 1.

Like parts are indicated by like symbols throughout the specification and drawings.

A generally indicates any suitable base frame or member provided, for example, with the anti-frictional and noise deadening studs or supports A¹.

Mounted on such base member is any suitable motor means, herein shown as the motor B, from which projects the motor shaft B¹ on which is the driving pulley B² adapted to engage and drive the belt B³, herein shown as of triangular cross-section, to engage the inclined faced channel B⁴ on the pulley B².

C is a knife supporting sleeve mounted upon the base A and including the shield portion C¹. It will be understood that the shield portion is continuous with or extends to the motor housing B and forms part of the gen-

eral upwardly projecting housing or frame member C¹.

Mounted within the sleeve portion C is an inner sleeve D in which are mounted the ball bearing tracks D¹ to support the balls D² opposed to the inner tracks D³ on the knife shaft D⁴. D⁵ are locking nuts whereby to secure the knife shaft and roller or ball bearing assembly together, the shaft D⁴ being enlarged as at D⁶ to engage the inner forward ball track D³. D⁷ is a channel pulley mounted on the shaft D⁴ adapted to receive about it the belt B³.

E is a knife disc proper secured to the shaft assembly for example by the screw E¹ and additionally secured to the pulley D⁷ for example by the screws E³. The knife disc is shown as convex and is peripherally cut away or recessed on its hollow face, as at E⁴ to leave a peripheral portion E⁵ projecting somewhat forwardly from the face of the knife, the inner face of which is preferably, but not necessarily, cupped.

Mounted on the forward face of the frame member C¹ is the fixed guard plate H which may be of any suitable material. At its left edge, as shown in Figure 3, it is arcuately cut away as at H¹, the arcuate portion penetrating or seating closely within the peripheral channel E⁴ of the knife E the axis of the knife being slightly tilted in a horizontal plane from perpendicularity to the plate, as shown in Figure 1 to bring the edge of the knife forward into the position shown in such figure, generally in the plane of the guard plate H.

J is a frame or housing member upwardly projecting from the opposite end of the base A. Mounted for rotation therewithin is the control shaft J¹ upon the inner end of which is the worm J². Such shaft is controlled by the external handle J³ provided with indicating symbols as at J⁴ aligned with the opposed pointing member J⁵.

Pivoted to the vertical rock shafts J⁶, J⁷ within the housing J are the levers or pairs of levers K, K¹, at the outer end of each pair of which are pivoted the blocks or strips K², to which are secured any suitable gauge plate K³, the surface of which may be slightly

convex or bowed, to conform to the cutting edge of the knife E since the active cutting portion of the knife, due to the angle at which it is set, is not in a vertical plane but 5 is slightly bowed forward. The right edge of said gauge plate K³, as shown in Figure 3, may be arcuately formed, as at K⁴, generally concentrically with the arcuate portion H¹ of the fixed guard plate. The distance 10 separating the opposed edges is, as shown in Figure 3, sufficient to permit the penetration therebetween of the peripheral portion E⁵ of the knife E.

Secured to the rock shaft J⁶ is a segment 15 worm gear K⁷ which meshes with and is driven by the worm J². A tension spring K⁸ is secured at one end to a lug K⁹ on the frame J and at its opposite end to one of the pivoted blocks or strips K². This spring serves 20 to hold the teeth in the segment K⁷ in close contact with the opposed teeth of the worm J².

Coiled around the upper part of the rock shaft J⁶ is a heavy spring K¹⁰, which is held 25 under compression against the under side of one of the bearing lugs K¹¹ by the collar K¹² which is secured to the rock shaft J⁶. The resulting friction acts as a brake, and tends to hold the gauge plate K³ in any position in 30 which it may be set by the operation of the handle J³.

L is any suitable receiving plate for receiving the material sliced by the knife and L¹ is any suitable control switch for 35 controlling the current to the motor of the motor housing B.

M is a track herein shown as of circular cross-section mounted for example on the supports M¹ upwardly projecting from the 40 opposite ends of the base A. The ends of the track are enclosed by the sheaths M² apertured to permit the penetration of the bolts or screws M³ headed as at M⁴ and upwardly extending through the base A, the support 45 members M¹, the sheaths M² and into the ends of the track M. Aligned beneath the track M is any suitable slide or rail M⁵ herein shown as of rectangular cross-section.

Mounted for movement along the track M 50 and the rail M⁵ is any suitable carriage or supporting member herein shown as including a body portion O and a meat engaging member O¹. Such meat engaging member includes a broad face O² slightly inclined to the horizontal and a narrower face O³ sharply inclined to the horizontal the two being generally perpendicular to each other. Downwardly depending from the body portion O is an arm or slide O⁴ with a depending finger O⁵ adapted to engage one side of the slide M⁵.

Mounted on the carriage O is a tube P which projects outwardly therefrom in general parallelism with the meat engaging face O² of the member O¹. Slidably mounted about the tube

P is the outer tube P¹. Screw-threaded to the end of the outer tube P¹ is any suitable head P² to the inner end of which may be secured, as to the eye P³, the coil spring P⁴, the opposite end of which is secured in relation to the carriage O as at P⁵. Slidably mounted upon the tube or guide P¹ is the guiding sleeve P⁶ with the laterally extending arm or bracket P⁷ to which may be secured the pusher plate P⁸, as by the intermediacy of the pin P⁹ which passes through the sleeve P¹⁰ on the arm P⁷.

The use and operation of my invention are as follows:

My slicing machine includes a motor driven 80 knife and a manually operated carrier or carriage for the work. I associate with the knife the guard plate masking all but the periphery of the cutting edge of the knife, and a gauge plate which is held in parallelism with the guard plate but is moved to or from the cutting plane, to adjust the thickness of the slice. In order to gauge the slice the work is thrust against the gauge plate. As this thrust continues until the slice is 85 entirely severed, I employ a guard plate to receive the thrust of that portion of the work which has passed the cutting edge. It is desirable to withdraw the work from contact, with gauge and guard plates, except during 90 the actual slicing operation. I find the type of carriage herein shown highly efficient, for example by the provision of an inclined work engaging member or surface, which is set at a sufficient angle to cause the work to recede 95 from guard and gauge plates unless positively thrust thereagainst. This recession may, at one extreme, with a relatively low narrow carriage, take the form merely of a tendency 100 on the part of the work to pull back from the gauge and guard plates, to prevent pressure of the work thereagainst. With a higher angle the work may actually physically recede as a body and under some circumstances it is 105 desirable to have the angle sufficiently high so that the work will slide bodily to the rear of the carriage.

I claim:

1. In a slicing machine, a knife and means for actuating it, a gauge plate and means for actuating it, a carriage and means for guiding it across the gauge plate and past the cutting edge of the knife, the carriage including a work support inclined downwardly and outwardly away from the knife, manually operable pusher means for moving the work upwardly across the work support and into close proximity to the cutting plane of the knife, spring means tending also to move said manually operable pusher means upwardly across the work supporting portion, said spring means tending also to resist the gravitational movement of the work downwardly across the work support and away from the cutting plane, and stop means to arrest the 110

115

130

spring thrust approach of the pusher means towards the gauge plate at a point spaced materially outwardly away from the cutting plane of the knife, whereby said spring means is adapted to operatively thrust pieces of work of predetermined length inserted between the pusher means and the gauge plate into operative contact with the gauge plate, and whereby work pieces of lesser length may be thrust against the gauge plate by manual operation of the pusher means.

2. In a slicing machine, a knife and means for actuating it, a gauge plate and means for actuating it, a carriage and means for guiding it across the gauge plate and past the cutting edge of the knife, the carriage including a work support inclined downwardly and outwardly away from the knife, manually operable means for moving the work upwardly across the work support and into close proximity to the cutting plane of the knife, spring means tending also to move said manually operable pusher means upwardly across the work supporting portion, said spring means tending also to resist the gravitational movement of the work downwardly across the work support and away from the cutting plane, and stop means to arrest the spring thrust approach of the pusher means towards the gauge plate at a point spaced materially outwardly away from the cutting plane of the knife, whereby said spring means is adapted to operatively thrust pieces of work of predetermined length inserted between the gauge plate and pusher means into operative contact with the gauge plate, and whereby work pieces of lesser length may be thrust against the gauge plate by manual operation of the pusher means, said pusher means and spring means including a pusher plate, a guide, generally perpendicular to the cutting plane, upon which said plate is mounted for longitudinal and rotary movement in relation to the guide, and a spring, positioned within said guide, and tending normally to urge said pusher plate toward the gauge plate.

Signed at Indianapolis, county of Marion and State of Indiana, this 30th day of August 1930.
